(57) **CLAIM**

The ornamental design for an utility deck, as shown and described.

DESCRIPTION

FIG. 1 is a top perspective view of an utility deck in a condition of use, showing my new design with a tailgate in a raised position and cabinet doors in closed positions; FIG. 2 is a top perspective view thereof, illustrated with the tailgate in a lowered position and the cabinet doors in open positions;

FIG. 3 is a rear elevational view thereof;

FIG. 4 is a front elevational view thereof;

FIG. 5 is a right-side elevational view thereof, the left-side elevational view being a mirror image thereof;

FIG. 6 is a top plan view thereof; and,

FIG. 7 is a bottom plan view thereof.

The broken lines showing a truck in FIG. 1 depict environmental matter and form no part of the claimed design. The broken lines in FIG. 7 depict portions of the utility deck that form no part of the claimed design.

1 Claim, 6 Drawing Sheets(56)
